UNITED STATES PATENT OFFICE

ROBERT M. SLATON, OF MADISONVILLE, KENTUCKY.

ROTARY-DISK HARROW.

SPECIFICATION forming part of Letters Patent No. 657,839, dated September 11, 1900.

Application filed September 21, 1899. Serial No. 731,190. (No model.)

To all whom it may concern:

Be it known that I, ROBERT M. SLATON, a citizen of the United States, residing at Madisonville, in the county of Hopkins and State 5 of Kentucky, have invented new and useful Improvements in Rotary-Disk Harrows, of which the following is a specification.

My invention relates to rotary-disk harrows; and one object is to provide means 10 whereby the inner ends are connected so nearly in line with the work as to leave no center ridge in the field, thus insuring thorough harrowing of the soil.

It is also an object to provide improved 15 bearings for the harrow, so that the friction will be lessened, choking prevented, and draft lightened; also, to provide improved clearers that prevent the clogging of the disks.

The invention consists in the novel construction and combination of parts herein- 20 after fully described and claimed.

In the accompanying drawings, Figure 1 is a perspective view of a harrow constructed in accordance with my invention. Fig. 2 is a 25 bottom plan view of the same. Fig. 3 is a longitudinal section of one of the gangs of disks, clearly showing the bearings and their location. Fig. 4 is a rear end view showing center couplings and clearers attached. Fig. 30 5 is a perspective view of one of the clearers detached.

In the said drawings the reference-numeral 1 designates the tongue of the harrow, to which are bolted two rearwardly-extending 35 curved tongue-irons 2, to the rear under sides of which are bolted two short bars 3. Bolted to said bars is a cross-bar 4, the outer ends of which pass between said curved tongue-irons and short bars, and to the center of this cross- 40 bar the rear end of the tongue is bolted. Secured to the cross-bar 4 is an upright plate 4^a, which serves to catch in the notches of the draw-bar 16. The lever 17 is pivoted to the draw-bar and passes up through the board 6 45 within reach of the driver and is designed to be operated to set the gangs of disks at the desired angle to the draft-line.

The numeral 5 designates an arch having 50 downwardly-curving ends the feet of which are bolted to curved tongue-irons 2 and short bars 3.

The numeral 6 designates a bucking-board

the front end of which is bolted to the top of a knee 7, the feet of which are bolted to the tongue 1. Said bucking-board is also bolted 55 intermediately to arch 5.

The parts thus far described constitute the main frame of my harrow.

The numeral 8 designates two channel-arches, which support the rotary disks. Said 60 arches are formed with legs curved downwardly, having feet at bottoms, the outer ends or feet passing between the tongue-irons 2 and short bars 3, having a pivoted connection therebetween. The ends of channel-arches 8 65 have downwardly-curving legs 9 and 10, provided at bottoms with feet 11 and 12. To said feet are secured coupling-plates 13 and 14. The rear end of coupling-plate 14 is connected to the front end of plate 13 by a link 15. To 70 the front end of the plate 14 a draw-bar 16 is pivotally connected, said draw-bar having a series of notches formed therein which engage the upright plate 4^a. Bearing-blocks 22 75 23 are bolted to the feet of the arches 8, and the rod 20 is supported in said blocks. The concavo-convex disks 19 are each provided with a central hole, through which the rod 20 passes, and said disks are spaced apart on said rod by the tubular sections or pipes 21. 80 I have shown four disks in each gang, but it will be understood that any suitable number may be used.

Bolted to arches 8 are clearers that consist of an arm 26, an elbow 27, and a saddle 28, 85 which embraces pipes 21. The object of said clearer is to prevent clogging of the disks.

In the large sizes, where three stocks may be needed, the tongue that is shown in Fig. 1 is shortened and a tongue is set off to one side, 90 as shown in Fig. 2.

The numeral 29 designates a driver's seat secured to the bucking-board 6.

In operation the disks will harrow and pulverize the soil, and as the inner ends of the 95 gangs are so nearly in line with each other and with the work they will leave no center ridge. The said gangs are adjustable by means of the lever 17 and draw-bar 16, with its series of notches that engage with plate 4^a 100 on cross-bar 4.

Having thus fully described my invention, what I claim is—

1. In a rotary-disk harrow, the harrow-

disks spaced apart on rods by intermediate sleeves, said disks being secured to arches pivoted at their outer ends to the frame, and their inner ends extending beyond the center or draft line of the harrow, flexible connections between the inner ends of the arches, and a lever attached to said flexible connections for changing the angle of draft, substantially as described.

10 2. In a rotary-disk harrow, two gangs of disks mounted to revolve on separate axles journaled at their outer ends in the harrow-

frame, the inner ends of said axles extending beyond each other and connected by a flexible coupling, and means for changing the 15 draft-angle of the axles and disks, substantially as described.

In testimony whereof I have hereunto set my hand in presence of two subscribing witnesses.

ROBERT M. SLATON.
